UNITED STATES PATENT OFFICE.

JOSEPH ALBERT WARREN, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITER FOR INTERNAL-COMBUSTION ENGINES.

1,161,555.

Specification of Letters Patent. Patented Nov. 23, 1915.

Application filed October 8, 1913. Serial No. 794,074.

To all whom it may concern:

Be it known that I, JOSEPH ALBERT WARREN, a citizen of the United States, residing at Sumter, in the county of Sumter and 5 State of South Carolina, have invented certain new and useful Improvements in Igniters for Internal-Combustion Engines, of which the following is a specification, reference being had to the accompanying drawing.

10 My invention relates to igniters for internal combustion engines, and particularly to igniters of the make-and-break electric spark type, and consists of an improved construction of the insulated electrode whereby same may be more thoroughly and permanently insulated from the body of the igniter than has heretofore been possible. A further object is to so place this electrode in the body of the igniter, that it may 15 be readily removed and replaced without disturbing its insulation.

20 Figure 1 is a view partly in section of the insulated member of an igniter constituting my invention. Fig. 2, a view partly in section of a complete igniter with the insulated member in place, and Fig. 3, an end view of the inside or cylinder end of the igniter shown in Fig. 2.

25 Like figures of reference denote the same parts wherever they are shown.

30 For the sake of illustration a well known form of igniter is shown, but as my invention may be used with any form of make-and-break igniter, I will not describe the complete igniter in detail, but only the assembly of the parts embodying my invention.

35 Make-and-break igniters are usually assembled by the engine manufacturer. As a rule, engine manufacturers are not skilled in the construction of electrical appliances and therefore many of them do not realize the importance of properly and thoroughly 40 insulating the parts of the igniter. It has been the practice to employ asbestos and shellac, or common cut mica for surrounding the insulated member of the igniter which has always been placed directly in the body 45 of the igniter, in consequence of which short circuits and other troubles often occur.

50 In the construction I employ it is possible for the insulated members of the igniters to be made by manufacturers familiar with in-

sulating parts from each other, and these manufacturers can sell the engine manufacturer these insulated members ready to mount in the igniter proper as the insulated members may be assembled as a separate part, like the ordinary spark plug. The 55 only work the engine manufacturer will do is purely of a mechanical character such as putting the part in the igniter. The result is an igniter in which the insulated electrode is properly constructed and so arranged that 60 same may be readily removed from the igniter body and replaced with a new member without disturbing the insulation or without the necessity for any electrical knowledge or 65 particular care on the part of the person 70 doing the work.

75 My improved construction of the insulated member of an igniter consists of the electrode stem 1, which is incased in a tube 2, from which it is insulated by washers of mica or other suitable insulation 3 and 4. The end of 1 is threaded, and it, the tube 2 and the insulation 3 and 4, are clamped together by means of nuts 5 and 6. To form a shoulder for insulation 3, I provide a metallic washer 7; which may be made integral with the stem 1.

80 It will be observed that the foregoing construction results in an open space 8 between the stem 1 and tube 2, as the insulation need not extend the entire length of the stem.

85 Tube 2 is threaded at 9 for a nut 10 by means of which it is clamped in the igniter body 11. The movable member of the igniter is shown at 12.

90 The parts shown in Fig. 1 are those that must be carefully insulated from the body of the igniter 11, and the face of the insulation 3 and 4 should be smooth and polished. When mica is used, after the mica has once been 95 compressed by nuts 4 and 5, it should not be disassembled or trouble will result. In constructions heretofore used, to remove the electrode stem 1 from the igniter body it was necessary to disassemble the insulation 100 surrounding the stem. This I obviate by simply unscrewing the nut 10, as tube 2 carrying the insulation and stem 1 may be slipped out of the body of the igniter 11 without in any way altering the pressure on 105 the insulation 3 and 4 or in any other way disturbing the insulation.

110 This construction enables the unskilled

to remove the insulated part of an igniter by simply taking off one nut, without any danger of causing a short circuit or in any other way affecting the electrical insulation or relative adjustment of the parts—all its being metal-to-metal.

This invention also obviates the necessity of the gas engine manufacturer doing any electrical testing on the igniters, which need only be placed in position by the gas engine manufacturer.

I claim—

1. In a make and break igniter, a body, a movable electrode mounted on the inner end 13 of a shaft extending through said body, and a coöperating fixed electrode comprising a metal tube flanged at one end and having a clear cylindrical opening through it from end to end, insulating bushings fitted to both 20 ends of the tube and having aligned openings through them centered on the axis of the tube but of less diameter than the inside diameter thereof, a metal plate or washer covering the exposed inner face of the inner 25 bushing, and a conducting rod of the same diameter as said openings extending through both bushings, with a head at the inner end thereof of somewhat larger diameter forming the anvil for the movable electrode, and 30 shouldered to rest against the washer covering the adjacent insulating bushing, with a nut in threaded engagement with the outer end of said tube to secure the same in the igniter body, and clamping means on the 35 outer end of said rod bearing against the outer face of the outer bushing in the tube.

Copies of this patent may be obtained for five cents each, by addressing the "Commissioner of Patents, Washington, D. C."

the diameter of said clamping means and of said bushing being less than the diameter of the threaded end of the tube, whereby the parts are all held firmly but detachably in 40 position, and the fixed electrode comprising the tube and the insulated rod may be removed from the igniter body as a unit by detaching the nut from the tube and slipping the same over the bushing and clamp- 45 ing means.

2. In a make and break igniter, a body, a movable electrode mounted on the inner end of a shaft extending through said body, and a coöperating fixed electrode comprising 50 a flanged metal tube extending through the body and provided with a nut on its outer end to clamp it therein, a single conducting rod extending through said tube with its inner end exposed as an anvil for 55 the movable electrode, said rod being centered in the tube but electrically separated therefrom by suitable insulation, and means on the outer end of the rod clamping the same rigidly to the tube, said means and 60 the insulation around the rod being of less diameter than the outer threaded portion of the tube, whereby the removal of the nut upon said tube will permit the withdrawal 65 of the fixed electrode as a unit from the body of the igniter.

In testimony whereof I hereunto affix my signature in the presence of two witnesses.

JOSEPH ALBERT WARREN.
